UNITED STATES PATENT OFFICE.

SAMUEL S. LAWS, OF NEW YORK, N. Y., ASSIGNOR TO THE GOLD AND STOCK TELEGRAPH COMPANY.

IMPROVEMENT IN PRINTING-TELEGRAPHS.

Specification forming part of Letters Patent No. **99,273**, dated January 25, 1870.

To all whom it may concern:

Be it known that I, SAMUEL S. LAWS, of the city, county, and State of New York, have invented a new and useful Improvement in Telegraphic Printing Apparatus; and I do hereby declare the following to be a full, clear, and exact description thereof, which will enable those skilled in the art to make and use the same, reference being had to the accompanying drawings, forming part of this specification, in which drawings—

Figure 1 represents an elevation of that side of my apparatus which contains the type-wheel, the inking-tape, the printing-lever, and mechanism for feeding the paper. Fig. 2 is an elevation showing the opposite side of the apparatus. Fig. 3 is a longitudinal vertical section of this apparatus. Fig. 4 is a plan or top view thereof. Fig. 5 is a diagram illustrating the electrical connections between the battery and the various parts of my apparatus.

Similar letters indicate corresponding parts.

This invention relates to certain improvements on that class of electrical instruments which I have described in Letters Patent granted to me December 31, 1867, and for which the application was filed in the United States Patent Office December 6, 1866, and also in Letters Patent granted to me March 24, 1868; and the object of my present improvements is in part to provide certain simple and novel means whereby letters, figures, or other characters can be printed and impressed upon paper or other suitable material from a type-wheel or denoting device, to which advance and retrograde movements can be imparted at pleasure for the purpose of readily and quickly bringing any desired type upon said type-wheel in proper relation to a platen or printing-lever for taking impressions from it, and it is especially designed to operate a number of these instruments in unison with or without local batteries.

My present improvement further provides for communicating any intelligence whatever, but especially for quoting the prices of gold, stocks, or other articles which fluctuate by eighths, by furnishing the type-wheel with the fractions $\frac{1}{8}$, $\frac{1}{4}$, $\frac{3}{8}$, $\frac{1}{2}$, $\frac{5}{8}$, $\frac{3}{4}$, and $\frac{7}{8}$, which represent these fluctuations, in combination with

the ten digits and all the letters of the alphabet and other suitable characters. It also provides for operating the platen or printing-lever, which is used for taking on paper or other material impressions from a type-wheel, by means of the direct action of the electro-magnet, the force thus employed being caused to act or to cease to act at pleasure, and thus to do its work independent of the movements of the type-wheel. It provides, further, for supplying ink to an endless inking-ribbon from a fountain, so that the same piece of ribbon can be used until worn out; also, for communicating the movements of the type-wheel arbor to the inking-ribbon, so that freshly-inked surfaces will be constantly brought opposite the types from which it is desired to take impressions; further, for keeping the inking-ribbons smooth and under proper tension, at the same time allowing it to be moved freely either forward or backward, as may be required; also, for regulating the tension of the paper and for printing in succession and interspacing the characters by moving the paper on which the impressions are made suitable distances by and simultaneously with the reciprocating action of the printing-lever; further, for so delivering the paper on which the impressions are made that each character printed will be exposed to view in a more convenient and immediate manner than heretofore; also, for adjusting each end of the printing-lever, so as to bring the armature of the printing-magnet in the proper position, and also the upper end of said lever into suitable relation to the periphery of the type-wheel, the platen-roller itself being also adjustable with reference to the faces of the types, so as to obtain an even and full impression; further, for a dial or indicating-disk upon the side of the type-wheel and for a stationary pointer before said disk, so that when said disk is properly adjusted the pointer will always point to and indicate upon the disk that character upon the type-wheel which is in proper position opposite the platen to give an impression, thereby enabling one to read off upon the indicating-disk any message received or sent simultaneously with the printing of such message; also, for working up the type-wheel to a given character automatically by

means of the stop lever, and if several machines are on the same circuit, and operated simultaneously, for bringing them into unison at pleasure; also, for employing each of the type-wheel circuits as a printing-circuit for the other, so that when the instrument is equipped with three magnets—one for the advance movement, a second for the retrograde movement, and a third for printing—the printing can be done at pleasure with any one of the three magnets, the current in all cases being distinctly separated from the one that operates the type-wheel. The interior numbers on the disk, from 1 to 24, have relation to the position of the traveling spring of the circuit-changer shown in Fig. 2 of the drawings; and I will here remark that this device, in combination with certain receiving-instruments, will be embodied in an application for a distinct patent.

In the accompanying drawings, the letter A represents the frame of my apparatus, and this frame forms the bearings for the shaft H', on one end of which is mounted the type-wheel H. This type-wheel consists of a circular plate or disk having types of suitable letters, numerals, fractions, or other characters upon its periphery, properly arranged, spaced, and constructed, so that each one will give a separate and distinct impression, and said type-wheel is situated on the outside of the frame A, so that its face is fully exposed to view. On this face is secured a disk, S, having characters printed, or otherwise produced, upon it in a circle corresponding to the characters on the types, but so situated in relation to a stationary pointer, p*, that if said pointer stands over the letter V, for instance, the type carrying the letter V on the type-wheel will be opposite the platen d, and that by these means the operator is enabled to read off during the operation from the letters on the disk S the message which he transmits or receives.

The construction of the platen d and its operation will be hereinafter explained.

The motion of the type-wheel is effected by means of two spring-pawls, p p, which act against a spurred or right and left ratchet-wheel, M, which is keyed upon the arbor H' of the type-wheel. Said pawls are secured on the upper ends of the vibrating levers J J, (see Fig. 3,) which extend from the armatures G* G'*, and they are arranged in such a manner that whenever the armature G* is attracted by its electro-magnet G the wheel M will be propelled in one direction, and when the armature G'* is attracted by its electro-magnet G' the wheel M is caused to move in the opposite direction. By these means an advance and retrograde movement can be imparted to the type-wheel H, and thereby the operation of bringing any desired character upon said wheel opposite to the platen is materially facilitated.

The construction of the pawls p p and their connection to the armature-levers is fully described in my patent of December 31, 1867, and

I do not therefore repeat it here, and I desire to claim in this present application only the combination of a mechanism with the type-wheel, which enables me to move said type-wheel readily in either direction and to retain it firmly in the desired position for the purpose of taking the impression.

A single magnet placed in an electrical circuit and provided with an armature upon an arm carrying a pawl and acting on a ratchet-wheel would, as is well known, give to a type-wheel an intermittent rotary motion in one direction, as would also a clock-train operated upon by a magnet-pallet; but it is obvious that the characters upon a type wheel thus moved could not be brought in proper position for taking impressions from them with the desired rapidity and convenience which is afforded by the use of means, substantially such as described, which will impart to the type-wheel the advance and retrograde movements, such movements being deemed of special value in reporting fluctuations of markets and exchanges, such as those of gold and stocks, produce, and the like. If, for instance, the operator has printed $\frac{1}{2}$ and the type-wheel remains still in position, and he wants to print $\frac{1}{4}$, it will only be necessary to go back one step from $\frac{1}{2}$ to $\frac{1}{4}$, instead of traveling forward entirely around until he comes to $\frac{1}{4}$, and so in printing words and numbers, and especially if in the hurry of the operation he has gone one step too far in one direction, it is only necessary to retrace that step instead of working the type-wheel clear round. Moreover, should anything happen to disable one of the type-wheel circuits the other will remain sound and capable of operating the type-wheel, though more slowly, and thus this double provision may prove a valuable alternative in local telegraph-lines, for which this instrument is especially designed.

The types on the type-wheel are supplied with ink by means of an endless ribbon, f, which is stretched over the flanged drum F' and flanged guide-rollers F² F³ and held under tension by the flanged ink-fountain F. The drum F' is geared together with the type-wheel shaft H' by a train of cog-wheels, so that the inking-ribbon is caused to move in either direction with the type-wheel, and consequently freshly-inked surfaces of said ribbon are brought opposite to the types for each new impression.

The ribbon is supplied with ink from the ink-fountain F, which consists of a hollow drum perforated on its periphery and covered by a strip of felt or other cloth, which prevents the ink from running out of the fountain any quicker than desirable. (See Fig. 1.) Said ink-fountain has its bearing on a pin secured in an arm, F*, which is pivoted to the frame A, so that the weight of the fountain itself will produce the desired tension of the inking-ribbon; and if this weight should be too great it can readily be relieved by a spring. By unscrewing the pivot of the arm F* the ink-

fountain can readily be taken off for the purpose of introducing a fresh supply of ink.

The guide-rollers F^2 F^3 are so arranged with relation to the type-wheel and platen that the inking-ribbon is caused to extend down between those parts in nearly a vertical plane, and the guide-roller F^2 is secured to the frame A by means of an arm, which can be made to swing toward or from the type-wheel, and by these means the inking-ribbon can be adjusted in the desired relation toward the type-wheel.

I will now proceed to describe the manner of actuating the platen for taking impressions from the characters of the type-wheel H, and premise by stating, as will be hereinafter more distinctly shown, that the movements of the type-wheel thus far explained are made and controlled independently of the movements of the printing mechanism, and that the impressions are taken when said wheel is at rest.

The platen d is mounted upon the upper end of an arm, D, that has its bearings on a pivot, secured in the frame A, and is made in the form of an elbow-lever, which I denominate the "vibrating printing or platen lever." The platen consists of a roller which revolves freely on its gudgeons, and it has its bearings in slots d^* , (see Fig. 1,) which bear on these gudgeons and serve to set the platen square with the faces of the types on the type-wheel, so that a full and even impression is obtained. The upright arm of the printing-lever is made in two parts, which are connected together by a pivot, d^2 ; and a set-screw, d^3 , in combination with a spring, d^4 , serves to adjust the platen in the proper relation to the type-wheel. The horizontal arm of the printing-lever carries the armature E^* of the printing-magnets E, and the stroke of said printing-lever is adjusted by double set-screws d^5 . (See Fig. 1.) The impression is taken on a strip, Z, of paper or other suitable material, and this strip passes over the platen d and between the same and the type-wheel, as clearly shown in Fig. 1.

The feed-motion of the paper is effected by means of pawls g g' , which are attached to the printing-lever and act upon a ratchet-wheel, g^2 , being drawn against the circumference of this wheel by a spring, g^3 . Said ratchet-wheel is mounted on a horizontal shaft, g^2 , which extends through the side of the frame A, and carries a drum, g^4 , in the plane of the type-wheel, and the face of this drum is serrated, so that it is enabled to carry the strip of paper along. This strip is held down upon the serrated circumference of the drum by spring-fingers a^6 , which are fastened to a bracket projecting from the frame A, and which are pressed down toward the drum by set-screws a^7 . (See Fig. 1.) The shape of these fingers is best seen in Fig. 4, and it will be readily understood that the same serve the double purpose of guiding the strip of paper and of pressing it down upon the serrated surface of the drum g^4 .

By the vibration of the printing-lever, as its armatures are attracted or released by the

printing-magnets, the paper is fed along in front of the type, the movements of the paper taking place partly before and partly after the impression has been made, since at every forward and backward stroke of the printing-lever, caused by the attraction of its armature and the recoil of the spring d^4 , the pawls g g' are caused to act upon the ratchet-wheel g^2 .

The strip of paper or other material upon which the impressions are made is taken from a reel, (not shown in the drawings,) and it passes up between the tension-rollers e^6 and through between a guide-roller, e^7 , and the platen to the feed-drum g^4 . The tension-rollers e^6 have their bearings in a bracket attached to the bottom part of the frame A, and they are pressed against each other by a spring, e^8 . By this arrangement the strip Z is kept taut and flat, and it is made to pass in a vertical direction through between the platen and the inking-ribbon f, and it is then carried directly onward in a horizontal plane, or nearly so, thereby exposing to view in a very prompt and convenient manner the letters, numerals, fractions, and other characters as rapidly as they are printed.

In order to obtain the requisite force for producing the impressions an additional armature, E^* , is applied to the printing-lever D, and this armature acts in conjunction with the additional printing-magnets E, the connection of which with the other magnets and with the battery will be hereinafter more fully explained.

Two magnets are used instead of one, because a greater attractive force is thus obtained from the same resistance of circuit than would be obtained by winding the coils around a single core. These two magnets E E' do the press work by their direct action, and by the co-operation of the recoil of the retractive spring the paper is fed along. The magnets G G', which operate the type-wheel, do the composing and inking by selecting and setting the types in proper positions to be printed from and bringing a fresh surface of the inking-ribbon in operation, and after this has been done the magnets E E' perform the press-work by supplying the blank paper, impressing and removing the impression out of the way of the next impression, and exposing it conveniently to view for being read.

When it is desired to work several instruments in unison on the same circuit, I apply to the arbor H' of the type-wheel an adjustable collar, H², provided with a toe, h³. Opposite to that toe I secure a tooth, h⁴, in the end of a lever, H⁴, which has its fulcrum on a shaft, h⁵, and which carries two armatures, h⁶, which present their edges to the sides of the cores of the printing-magnets E E', so that they do not interfere with the action of the front armatures, E* E'*², of the printing-lever. (See Fig. 3.) A spring, h⁷, holds the lever H⁴ back, so that the tooth h⁴ will clear the toe h³; but if the upper end of the lever H⁴ is only slightly depressed the tooth h⁴ intercepts the toe h³.

and stops the type-wheel in any given position, according to the position previously given to the toe h^2 . If, therefore, a light current is passed through the printing-magnets E E' of a number of instruments and the type-wheels are caused to revolve until the toes h^3 of the several instruments are intercepted by the tooth h^4 on the stop-levers, the type-wheels of the several instruments will be brought into unison, provided the collars H^2 have been properly adjusted. This result is especially valuable in working a system of instruments in reporting, since, on account of the slight force necessary to operate this stop-lever, a separate circuit is not required, as a light current can be thrown through the printing-magnets over their circuit without imparting any motion to the press-lever, as will be more clearly understood from the subsequent explanation of the manipulations of the currents.

I will now proceed to explain the connection of the various magnets and manipulations of the circuits.

In Figs. 2, 4, and 5 are shown two pairs of springs, r^{27} r^{28} , a detached view of one pair of which is represented in Fig. 6. These springs are secured to beds t t' , of hard rubber, and are provided with platinized ends u u' , which bear against the points 13 and 14 or 10 and 12. The current always goes in on one of these springs and out of the other of each pair, and the course of the current is determined by the position of the lower platinized ends of said springs. When the current goes through the springs r^{27} and r^{28} , Fig. 5, and the points 13 and 14, the magnet G is charged and its armature is attracted, and the stud j^9 , secured in the armature-lever J, (see Fig. 2,) pushes the springs r^{25} and r^{26} back against the points 17 and 18 and holds them there till the circuit is broken, when the lever J and the springs r^{25} and r^{26} are allowed to fall back to their original position, causing said springs to bear on the points 15 and 16; but while the springs r^{25} and r^{26} bear against the points 15 and 16, their circuit is completed through the type-wheel magnet G', and while said springs are in contact with the points 17 and 18 the circuit is established through the printing-magnets E E'. The same holds true of the opposite side, each type-wheel magnet, when and while being charged, switching the other type-wheel magnet out of circuit and the printing-magnets into circuit, as will be presently more fully explained.

The course of the current from the battery is controlled by the keys 1 2 3, Fig. 5. The keys 2 and 3 throw on the entire battery-current, but the effect of the key 1 can be changed by the switch s . If this switch is brought over the button s^2 , then only a part of the battery is thrown on; but if the switch s is brought in contact with the button s' the whole battery is thrown on. The key 1 connects with the binding-screws 6 and 7, the key 2 with the binding-screws 4 and 5, and the key 3 with

the binding-screws 8 and 9. When the key 3 is closed, the key 2 being open, the current of the entire battery passes from the pole B through the wires 25 and 24, binding-screw 8, wire 28, spring r^{28} , screw 13, to the magnet G, and back through screw 14, spring r^{27} , wire 27, key 3, and wire 23 to the opposite pole, B', of the battery, thereby operating the type-wheel one step (at each closure) to the left or in a retrograde direction. If the key 3 is opened and the key 2 is closed, the current passes from the battery through binding-screw 4, wire 25, spring r^{25} , screw 16, magnet G', and back through screw 15, spring r^{26} , wire 26, key 2, and wire 23 to the battery, operating the type-wheel to the right or in a forward direction; but if the key 3 be first closed, and while it is kept closed the key 2 be closed, the current of key 2 will not go through the type-wheel magnet G', but through the printing-magnets E E', as follows: B, 4, 25, 17, 20, E, 19, E', 18, 26, s , key 2, 23, B', and as long as the key 3 is kept closed the closing and opening of key 2 will not operate the type-wheel, but the printing mechanism, because the closing of key 3 causes the current-springs r^{25} and r^{26} to be pushed from the points 15 and 16 against the points 17 and 18, and thus cuts the type-wheel magnet G' out of circuit; but the instant the key 3 is opened the springs r^{25} and r^{26} fall back against the points 15 and 16, and the circuit through the type-wheel magnet G' is established, (provided the key 2 be closed.) In like manner, if the key 2 be first closed and kept closed, the manipulation of the key 3 will not operate the printing-magnet G, but the printing-magnets E E', and thus each of the keys 2 and 3 may be used to print for the other. Each of them, while the other is open, operates its type-wheel magnet and that alone, and while the other is closed each operates the printing-magnets and them alone, and hence my instrument with its peculiar advance and retrograde movements is capable of doing its complete work as a printer with two wires. If desired, however, my instrument may be worked with three wires, and in this case the key 1 is brought into operation. By closing this key the current passes from pole B through 25 24 6 22 20, magnet E, 19, magnet E', 19 21 7, key 1, switch s , button s' to pole B', the entire force of the battery being applied to do the press-work; but if the switch s is brought on the button s^2 , then a small battery force is exerted that will leave the printing mechanism inoperative, but is sufficient to deflect the stop-lever H^4 , the operation and object of which have been previously described. The stop-lever will of course also act when the printing-current is thrown on; but as the type-wheel is then at rest it makes no difference even if its tooth comes against the toe of the collar H^2 , for when the circuit is broken at key 1 all the armatures of the printing-magnets, whether on the faces or sides of their cores, are at once retracted, thus clearing the printing-lever from the face of the type-wheel

and the tooth of the stop-lever from the path of the toe of the collar H^2 and leaving the type-wheel perfectly free to move under the impulse of its proper magnets in either direction.

By providing each double-action printer with six binding-screws and three wires any number of such instruments may be placed in line and operated simultaneously and automatically, delivering their messages wherever placed, only one single set of three keys or their equivalents and a single operator being required for the performance of the entire work of transmitting such intelligence as it may be desired to communicate.

Where it is found expedient to operate the instruments with local batteries, each wire of the three main lines would require its own relay for each local circuit.

My plan of building the lines is to use a continuous unbroken metallic circuit without the use of ground-circuit at all, as the liability of derangement is thereby lessened and the instruments can be located all along the lines going out and coming back.

I am aware that the type-wheels of telegraphic printing-instruments have heretofore been moved step by step by means of clock-work controlled by magnet-pallets and otherwise, and also by the armature-lever of an electro-magnet, but always in one direction only. In all such instruments, however, which have heretofore come under my observation, a single wire was considered a *sine qua non* and I have only quite recently found more than one wire in the instrument described by Henry N. Baker in his patent dated April 29, 1856. He distinctly sets forth two circuits and two keys—one for operating the type-wheel step by step—and the other for taking impressions from the types while the type-wheel is at rest.

I do not therefore claim as my invention the use of separate circuits or currents—one for operating the printing mechanism and the other for operating the type-wheel; but

What I claim as new, and desire to secure by Letters Patent, is—

1. The combination, with the type-wheel H , in a telegraphic printing apparatus, of mechanism, substantially such as described, for imparting to said wheel a step-by-step motion in an advance or retrograde direction, as set forth.

2. The endless inking-ribbon passing between the type and paper, in combination with the type-wheel and printing-lever of a tele-

graphic printer, substantially in the manner set forth.

3. Imparting to the endless inking-ribbon of a telegraphic printing-instrument a feed motion by gearing from the type-wheel shaft, substantially as described.

4. The ink-fountain F , in combination with the endless inking-ribbon, type-wheel, and printing-lever of a telegraphic printer, substantially as set forth.

5. The endless inking-ribbon combined with a cylindrical weight, F , substantially as specified, for maintaining the proper tension on said ribbon, as specified.

6. The arm of the printing-lever which carries the impression-roller, made in two parts connected by a hinge-joint and controlled by a spring and set-screw, substantially as and for the purposes described.

7. The serrated drum g^6 , ratchet-wheel g^3 , and pawls g^4 , in combination with the printing-lever D and its recoil-spring, substantially as and for the purposes set forth.

8. Two magnets arranged to act in the manner specified upon the impression-lever, in combination with the type-wheel, substantially as specified.

9. The unison lever H^4 , operated by an independent electric circuit, in combination with the type-wheel or indicating device actuated by a separate electrical circuit, substantially as and for the purposes described.

10. The arrangement of an armature acting upon the side of the core of an electro-magnet in addition to the armature acting on the face of said core, substantially as and for the purposes set forth.

11. The electrical circuits for effecting an advance or retrograde movement of the type-wheel, in combination with the separate electrical circuit for effecting the printing, substantially as specified.

12. The electrical circuits arranged and connected, substantially as specified, for effecting an advance or retrograde movement of the type-wheel, and either serving to give the impression when the other circuit is closed, substantially as specified.

13. A type-wheel containing letters, figures, and fractions or fractional signs to be impressed upon a strip of paper by magnetism, substantially as specified.

S. S. LAWS.
